(57) **CLAIM**

The ornamental design for a universal remote control with cooperating charging base, as shown and described.

DESCRIPTION

FIG. 1 is a three quarter top, front, right side perspective view of a universal remote control with cooperating charging base showing my new design;

FIG. 2 is a three quarter top, front right side perspective view of just the universal remote control per se showing my new design shown separately to illustrate portions of the claimed design not visible in FIG. 2;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a three quarter top, front, right side perspective view of just the charging base per se showing my new design shown separately to illustrate portions of the claimed design not visible in FIG. 2;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof; and,

FIG. 15 is a bottom plan view thereof.

It is to be understood that any portion of any figure shown in broken lines are for environmental purposes only and form no part of the claimed design.
